Primary Examiner — Cynthia R Underwood

(74) Attorney, Agent, or Firm — QuickPatents, LLC;
Kevin Prince(57) **CLAIM**

The ornamental design for a bullet shaped wire separator, as shown and described.

DESCRIPTION

FIG. 1 is a front perspective view of a bullet shaped wire separator, showing our new design;

FIG. 2 is an exploded front perspective view of FIG. 1;

FIG. 3 is an alternate front perspective view thereof;

FIG. 4 is an exploded view of FIG. 3;

FIG. 5 is a rear perspective view thereof;

FIG. 6 is an exploded rear perspective view of FIG. 5;

FIG. 7 is an alternate rear perspective view thereof;

FIG. 8 is an exploded view of FIG. 7;

FIG. 9 is a front elevational view thereof, the rear elevational view being a mirror image thereof; and,

FIG. 10 is an exploded front elevational view of FIG. 9.
